METHOD OF MAKING EXPANDED METAL GRATINGS

Frederick A. Gruetjen, Milwaukee, Wis., assignor to A. O. Smith Corporation, Milwaukee, Wis., a corporation of New York

Application March 31, 1947, Serial No. 738,255

3 Claims. (Cl. 113—116)

1

This invention relates to method of making expanded metal grating such as grating to be employed as a tread or walkway for railroad freight cars and the like.

One object of the invention is to provide an expanded metal grating in which the bond or tread surface is substantially vertical.

Another object is to provide a method of making an expanded metal grating in which the tread is provided with teeth in the initial cutting of the metal before expansion of the same.

A further object of the invention is to provide a grating at considerably less cost than previous gratings.

A further object is to provide a metal walkway of substantial rigidity with a decrease in metal and weight over previous constructions.

A further object is to provide a metal grating with integral longitudinal side bars.

Another object of the invention is to provide an improved method for fabricating a metal grating and which has integral side bars.

These and other objects of the invention will appear hereinafter in connection with the following description of an embodiment of the invention as illustrated in the accompanying drawings.

In the drawings:

Figure 1 is a plan view of the completed grating;

Fig. 2 is an elevational view of the side of the grating first formed in making the grating;

Fig. 3 is an elevational view of the side of the grating last formed in making a grating;

Fig. 4 is an enlarged section taken on line 4—4 of Fig. 1;

Fig. 5 is an enlarged section taken on line 5—5 of Fig. 1;

Fig. 6 is a perspective view of a portion of the completed grating;

Fig. 7 is a top plan view of the first step of the operation;

Fig. 8 is a front side elevation of Fig. 7 showing the table and cutting dies;

Fig. 9 is a top plan view of the second step of the operation showing the cutting dies in section;

Fig. 10 is a front side elevation of Fig. 9;

Fig. 11 is a side elevational view showing the sheet after successive forming steps;

Fig. 12 is a top plan view of the finished sheeting after completion of the last cutting and forming operation;

Fig. 13 is a fragmentary perspective view of Fig. 12;

Fig. 14 is an end elevational view showing the sheeting in place on a slotted die ready to be rectified into the grating of the invention;

Fig. 15 is an end elevational view showing the rectifying of the treads to vertical position; and

Figs. 16 and 17 are detail views showing the upsetting of the first formed edge into bar and tread alignment, shown in Fig. 2.

2

In the drawings there is shown an expanded metal grating or walkway, the body portion of which comprises a plurality of horizontal rows of transversely spaced vertical bonds or treads 1 with each row of treads offset or staggered from the adjacent rows, and treads 1 of one row integrally connected to the offset treads of the next adjacent rows by the diagonally extending strands 2 to provide the grating with a plurality of hexagonal shaped openings 3. Strands 2 are slightly twisted in fabrication and each strand 2 is approximately one-half the cross-section of a tread 1. Of a pair of strands extending between treads 1, one strand extends from the bottom of one tread 15 in the one row to the top of the tread in the next adjacent row while the other strand 2 in the first mentioned row extends from the top of the tread thereof to the bottom of the tread in the other next adjacent row.

20 The grating is bounded on one longitudinal side by the integrally formed vertical bar 4 and on the opposite longitudinal side with the integrally formed vertical bar 5. Bars 4 and 5 are connected to treads 1 by the integral strands 2 corresponding to the strands in the body of the grating.

25 Bar 4 is provided with the longitudinally spaced treads 6 corresponding in cross-section to treads 1 of the body of the grating and having the same vertical cross-section as treads 1. Treads 6 of bar 30 4 are spaced from the nearest treads 1 of the body 4 of the grating by vertical openings 3 as are provided in the body of the grating.

35 The treads 7 of bar 4 are longitudinally spaced in bar 4 between treads 6 therein and are transversely spaced from the nearest treads 1 of the grating by vertical openings 8 which are approximately one-half the cross-section of vertical openings 3 previously described.

40 Treads 7 of bar 4 are approximately one-half the cross-section of treads 1 and 6 and an upset operation, as will be described, is employed on treads 7 in fabrication to provide treads 7 as a part of the common tread surface of the grating and also to take up the metal at the forward side of the grating in the initial expanding operation 45 to be described.

45 Bar 5 provides a continuous longitudinal tread surface with alternate portions of bar 5 corresponding to the cross-section of treads 1 and 6 and intermediate portions thereof being about one-half the cross-section of treads 1 and 6 and corresponding to treads 7 of bar 4.

50 Teeth 9 are provided in the upper edge of treads 1, 6 and 7, respectively, to make the treads on the grating non-slip in service.

55 End bars 10 close the grating on each end and have suitable apertures 11 to receive the tabs 12 on the ends of the bars 4 and 5, and the end treads 1 of the body portion of the grating.

60 Tabs 12 are bent over against the outer sur-

face of bars 10 and may be secured thereto as by electric resistance welding. End treads 1 and 6 and bar 5 have abutments at each side of tabs 12 to bear against bars 10 to effectively brace the grating at the ends.

Under one method of making the grating the flat metal sheet 13 which is to be expanded is first provided with tabs 12 on opposite ends at predetermined spaced positions. Tabs 12 are shown on flat sheet 13 in Fig. 7 and the method of cutting the tabs is not shown in the drawings as it forms no part of the present invention.

Sheet 13 is then placed on a table 14 with the working edge at one side, and suitable means, not shown, is provided to move sheet 13 forwardly and sidewardly in the fabricating operation, as will be described.

Sheet 13 is initially moved forwardly on table 14 to a line where the longitudinal side portion which forms bar 4 of the grating projects from the table about half the height of a tread 1 and the sheet is then engaged at the working edge of the table by the downwardly moving longitudinally spaced cutter dies 15, the end view of one such die being shown in Fig. 11.

Dies 15 cut a plurality of spaced longitudinal slots 16, as shown in Fig. 7, in sheet 13 in line with the first tabs 12 on the opposite sides of the sheet and previously provided thereon as described. In cutting slots 16, the die also cuts teeth 9 in the sheet centrally of slots 16 which latter appear on treads 7 of bar 4 as the tread surface. In cutting slots 16, the dies depress or expand the longitudinal side portion of sheet 13 to a lower plane than the body of the sheet, as shown in Fig. 8, to form a portion of bar 4 when the sheet is finally fabricated into a grating.

Sheet 13 is next moved sidewardly and then forwardly on table 14 and a second row of spaced longitudinal slots 17 with teeth 9, as shown in Fig. 9, are cut therein at the edge of table 14 by the downwardly moving die cutters 15. Slots 17 are located on a line equally spaced between the first and second tabs 12 of the sheet. Slots 17 are also offset or staggered from slots 16 due to the sideward movement of the sheet described, before the same is moved forwardly. As the cutter dies 15 move downwardly to form slots 17, the portions between slots 16 and 17 and in advance of slot 17 are depressed or expanded to a lower plane, as shown in Fig. 10. Strands 2 join the treads 6, formed by cutting slots 17, to the sheet.

Sheet 13 is next moved sidewardly on table 14 back to the transverse position where slots 16 were cut and then forwardly to cut an additional row of slots in line with slots 16 but offset from slots 17.

Thereafter sheet 13 is alternately shifted sidewardly and forwardly, as described, with first one row of slots being cut and intermediate portions of the sheet between the rows of slots being depressed by cutter dies 15, followed by another row of slots being cut at locations offset from the previous row of slots and intermediate portions of the sheet being depressed until the rear end of the sheet is within approximately half a tread height from the cutting die, as shown in Fig. 12. Fig. 11 is a side elevational view showing sheet 13 after a number of successive forming steps.

In the final cutting and depressing operation on sheet 13, the slots 18 are cut in the same manner as slots 16 and 17 and the intermediate portions of the sheet between slots 18 and the previously cut slots are depressed, as shown in

Fig. 13. The side longitudinal portion 19 of sheet 13 is held on table 14 by suitable means and in the final forming of the grating, to be described, portion 19 becomes side bar 5 with the latter being connected to the treads 1 by strands 2.

The formed sheet 13 is finally fabricated into the grating of the invention by a rectifying operation under which the tread portions and bars of the grating are straightened to a vertical position and strands 2 are slightly twisted.

In the rectifying operation the slotted sheet is placed on die 20, as shown in Fig. 14, with the side which becomes the bottom of the grating in service faced upwardly and the upper die 21 is brought into contact with treads 1 of the body portion of the grating and the longitudinal side portions. Die 21 moves the treads and side portions downwardly into the vertical spaced slots 22 of lower die 20 to straighten the treads to vertical position with the side portions forming longitudinal bars 4 and 5.

The grating is removed from dies 20 and 21 and the tread portions 7 on bar 4 are then upset to align with the treads 1 and 6, as shown in Figs. 16 and 17, to form a common tread surface throughout the grating by treads 1, 6 and 7, respectively, and the longitudinal extending tread of bar 5.

End bars 10 are next assembled to the grating by inserting tabs 12 on the grating through suitable holes 11 in end bars 10 and then turning the tabs against the outer face of each bar. The tabs may be welded to the bars by electric resistance welding. Lugs, not shown, may be welded to the bottom of the grating to bolt the same in place.

The invention provides a generally lightweight grating of sufficient strength and rigidity to stand up effectively under service requirements.

The invention also provides a method of providing integral longitudinal side bars and vertical treads which form a good footing in the common tread surface of the grating on which there is no danger of tripping.

Various embodiments of the invention may be employed within the scope of the accompanying claims.

I claim:

1. The method of forming a grating from expanded metal, which comprises cutting offset longitudinal slots in flat metal sheeting and expanding the sheeting to form rows of bond portions and side bars integrally joined by strands extending therebetween, subjecting the bonds and bars to a forming operation to rectify the same to a vertical position and to provide a common tread surface thereof, and upsetting intermediate portions of the first formed bar of the grating to bring said portions into the plane of the common tread surface of the grating.

2. In the method of forming integral side bars on grating formed from expanded metal sheeting by cutting slots therein and expanding and rectifying the uncut portions of the sheeting ahead of said slots to provide vertical treads therein on a common plane, the steps comprising cutting the last row of slots at a line removed from the rear edge of the grating about one-half the height of a tread of the completed grating to leave the rear edge portion of the sheeting as one side bar of the grating, turning said formed sheeting over and upsetting the forward edge portions of the sheeting ahead of the slots first cut in the sheeting in the direction of the common plane of the treads to form the same as a part thereof and

complete the forward edge as another side bar of the grating.

3. The method of forming a grating from expanded metal sheeting with said grating having integral side bars, which comprises cutting a plurality of spaced longitudinal slots in said sheeting near the forward edge thereof and expanding the edge portion of said sheeting ahead of said slots, cutting a second row of spaced longitudinal slots offset and spaced from said first row of slots and expanding the portions of the sheeting intermediate the first and second row of slots and ahead of the second row of slots, then successively cutting rows of slots in said sheeting with each row of slots offset from the previously cut row and expanding the sheeting ahead of the slots last cut until the last row of slots is cut adjacent the rear edge of the sheeting leaving the rear edge portion free to form a side bar of the grating, operating on said grating to rectify the uncut portions of said grating to a generally

vertical position to form a common tread surface, and upsetting the forward edge portion of said sheeting ahead of the slots first cut therein to bring the same into the plane of the portions of the grating forming the common tread surface thereof.
